Specification for Design.

Patented Nov. 28, 1911.

Application filed June 14, 1911. Serial No. 633,205. Term of patent 7 years.

To all whom it may concern:

Be it known that I, FRANK NUZZO, a citizen of the United States, residing at Pana, in the county of Christian and State of Illinois, have invented a new, original, and ornamental Design for Quarters for Shoes, of which the following is a specification, reference being had to the accompanying drawings, forming part thereof.

Figure 1 is a plan of the right quarter for shoes. Fig. 2 is a plan of the left quarter

for shoes. Fig. 3 is a plan of a shoe showing the quarters in their proper positions, the vamp of the shoe being shown in dotted lines.

I claim:

The ornamental design for a quarter for shoes, as shown.

FRANK NUZZO.
